FIG. 1

The back not shown is a mirror image of the front.

The characteristic features of this design reside in the configurations shown in full lines on the drawing.

I claim:

The ornamental design for a bottle, substantially as shown and described.
